NORMAN L. SNOW AND WILLIS P. THOMAS, OF DETROIT, MICHIGAN, ASSIGNEES TO
DIAMOND POWER SPECIALTY CORPORATION, OF DETROIT, MICHIGAN, A CORPORA-
TION OF MICHIGAN

BOILER CLEANER

Application filed June 14, 1928. Serial No. 115,971.

The invention relates to boiler cleaners and refers more particularly to a blower element construction. One of the objects of the invention resides in an improved blower element and discharge nozzle construction affording a simple and efficient method and means for mounting the nozzle in the blower element.

Referring to the drawings in which like reference characters indicate corresponding parts;

Figure 1 is a view showing a portion of the blower element,

Figure 2 is a sectional view thereof along 15 2-2 of Figure 1,

Figure 3 is a fragmentary sectional view of the blower element illustrating one manner of uniting the nozzle with the blower element,

Figure 4 is a sectional view through a 20 blower element illustrating the initial step of a modified manner of securing a nozzle to a blower element,

Figure 5 is a like view illustrating the next 25 successive step in securing the nozzle to the blower element,

Figure 6 is a sectional view of a blower element of slightly different construction illustrating the application thereto of the nozzle securing means shown in Figures 4 and 5.

Figure 7 is a sectional view through a blower element illustrating the initial step of another modified manner of securing a nozzle to a blower element,

Figure 8 is a like view illustrating the next 35 successive step in securing the nozzle to the blower element,

Figure 9 is a sectional view through a blower element illustrating the initial step of a still further modified manner of securing

40 a nozzle to a blower element, and

Figure 10 is a like view showing the next successive step in securing the nozzle to the blower element.

In the drawings reference character 10 45 represents a portion of a blower element which may be formed from a strip of suitable material by overlapping the edges thereof as shown in Figures 2-5 inclusive. The overlapped portions may be secured together 50 as shown in Figures 1 and 2 by mounting

therein through suitable registering openings in the overlapping portions one or more nozzles 11 which further function to project jets of cleaning fluid adjacent parts of the boiler to be cleaned. The nozzles may be secured in 55 place by any suitable means such as expanding, welding, etc. Thus the discharge nozzles serve as rivets to pin together the overlapping edges of the strip.

In Figure 3, the nozzle 11^a may be welded 60 to the overlapping edges of the blower element strip 10 as by the usual spot weld method. Electrode 12 may be shaped to approximate the expanding walls of the Venturi nozzle. When electric current is supplied by circuit 13 to electrode 12, this circuit including the blower element, and the electrode 12 pressed down within the nozzle as shown in Figure 3, sufficient heat is readily 65 produced thereby to weld the nozzle into the wall of the blower element.

With reference to the form of our invention illustrated in Figures 4 and 5 nozzle 11^b may be inserted from the interior of the element 10 into suitable registering openings 15 in the overlapping portions of the element. This nozzle is provided with a shoulder 14 which abuts the inner periphery of the element opening 15 and limits the outward 70 movement of the nozzle in this opening. The opening 15 is tapered while the upper outer walls 16 (in the position of the parts as shown in Figure 4) are straight or non-tapering affording clearance increasing progressively radially outwardly. Likewise the interior walls 17 of the nozzle are non-tapering while the lower end portion 18 is fashioned to form the throat of the standard Venturi 75 expanding nozzle.

Tool 20 fitted with a tapering head 21 is 80 driven into the nozzle, causing expansion of the nozzle corresponding to the taper of the tool head 21, this taper being that desired to fashion the nozzle expanding portion according to standard Venturi proportions. Thus the expanding portion is fashioned continuously with the throat portion 18 to form 85 a complete Venturi nozzle. At the same time the upper portion of the nozzle is expanded 90 into contact with the tapered walls 15 of the 100

blower element and is thus securely held in place. To prevent the nozzle being driven through the opening 15 anvil 22 may be provided, located beneath the nozzle by a handle rod 23 which may extend longitudinally of the element to a point outside the element where it may be conveniently manipulated.

This same method of nozzle installation may be employed in a blower element constructed of seamless steel, or welded tubing. Thus as shown in Figure 6 nozzle 11^e is provided with shoulder 14 and may be similarly mounted in element 10^e, the latter being closed ended at 24 in the customary manner.

In Figures 7 to 10 inclusive, we have illustrated modified methods and means of installing nozzles in blower elements consisting of inserting a nozzle into an opening in the element from the exterior thereof and then expanding the nozzle firmly into place.

Nozzle 11^a as shown in Figure 7 is placed in the tapered opening 25 from the exterior of the element. On the nozzle interior, the upper portion is tapered at 26 while the lower portion (except for the lower throat portion 28) is of straight or non-tapering wall construction as at 27. This nozzle may be driven into place by a suitable tool as previously described in connection with Figures 4 and 5, the nozzle taking the form shown in Figure 8. Thus the expanding portion of the nozzle is shaped to the desired Venturi form. The expanding operation causes displacement of the metal to form expanded beads or portions 29 and 30 exteriorly and interiorly of the blower element respectively. Thus the nozzle is held firmly in place between these enlarged portions. The nozzle may be more readily expanded if heated.

The nozzle assembly shown in Figures 9 and 10 is substantially identical with that shown in Figures 7 and 8 with the exception that the opening 25' in the element 10^e is non-tapering or straight-walled to receive the nozzle 11^e. The expanding action is substantially identical with that described in connection with Figures 7 and 8 except that the flow of metal of the nozzle 11^e is somewhat more pronounced in forming the beads or portions 29' and 30'.

Nozzles of the various forms illustrated may be installed as described in either ordinary steel blower elements or in blower elements constructed of a material alloyed to provide characteristics affording resistance to the destructive agencies set into action by the operation of the boiler.

What we claim as our invention is:

1. A boiler cleaner blower element comprising a tubular member having overlapping edges and a nozzle securing said edges in overlapping relation and providing discharge for a jet of cleaning fluid.

2. The method of fastening a Venturi nozzle and assembling the same with a tubular

soot blower cleaner member consisting in forming an opening in the wall of said member, inserting the nozzle in said opening, and expanding the nozzle in said opening to firmly seat the nozzle therein and simultaneously fashioning an expanding Venturi jet discharge portion in said nozzle. 70

3. The method of fashioning a Venturi nozzle and assembling the same with a tubular soot blower cleaner member consisting in forming an opening in said member, inserting a nozzle formed with a Venturi throat portion in said opening, and expanding the nozzle in said opening to firmly seat the member therein and simultaneously fashioning a 80 Venturi expanding portion communicating with said Venturi throat portion. 75

4. The method of fashioning a Venturi nozzle and assembling the same with a tubular soot blower cleaner member consisting in forming an opening in said member, the bounding walls of said opening being substantially frusto-conical, inserting a nozzle in said opening, and expanding the nozzle in said opening to fashion a Venturi jet expanding portion and simultaneously causing a portion of the nozzle to flow so as to form a shoulder engageable with the tubular member adjacent the opening therein. 85 90

5. The method of fashioning a Venturi nozzle and assembling the same with a tubular soot blower cleaner member consisting in forming an opening in said member, the bounding walls of said opening being substantially cylindrical, inserting a nozzle in said opening, and expanding the nozzle in said opening to fashion a Venturi jet expanding portion and simultaneously causing a portion of the nozzle to flow so as to form a shoulder engageable with the tubular member adjacent the opening therein. 95 100

6. The method of mounting a nozzle in a tubular soot blower cleaner member consisting in forming an opening in said member, inserting a nozzle in said opening and exerting a pressure interiorly of the nozzle to expand the nozzle in said opening to cause a portion of the nozzle to flow so as to form a shoulder engageable with the tubular member adjacent the opening therein. 110 115

7. The method of mounting a nozzle in a tubular soot blower cleaner member consisting in forming an opening in said member, inserting in said opening a bored nozzle provided with a shoulder adapted to contact with the interior surface of said tubular member adjacent the opening therein and exerting a pressure interiorly of said nozzle to expand the portion of said nozzle projecting beyond the exterior surface of said tubular member so as to cause a portion of the nozzle to flow to form a shoulder engageable with the said exterior surface of said tubular member. 120 125

8. The method of fashioning a nozzle and mounting the same in a blower element which 130

5 consists in forming an opening in the element, inserting a nozzle in said opening, and expanding said nozzle in said opening, to firmly seat the same therein, while simultaneously fashioning a jet opening in said nozzle.

9. The method of shaping a nozzle and mounting the same in a blower element which consists in forming an opening in said element, inserting in said opening a bored nozzle, and expanding said nozzle in said opening to firmly seat the same therein while simultaneously shaping the bore in said nozzle to form a jet opening of a predetermined contour.

10 15 In testimony whereof we affix our signatures.
